UNITED STATES PATENT OFFICE

CLEMENS KAMMERER, OF NEW YORK, N. Y.

DESIGN FOR A COMBINED PURSE MIRROR AND POUCH

Application filed December 31, 1930. Serial No. 38,157. Term of patent 3½ years.

To all whom it may concern:

Be it known that I, CLEMENS KAMMERER, a citizen of Germany, residing at New York, in the county of Queens, in the State of New York, have invented a new, original, and ornamental Design for a Combined Purse Mirror and Pouch, of which the following is a specification, reference being had to the accompanying drawing, forming a part thereof.

The figure is a perspective view of a combined purse mirror and pouch, showing my design. The reverse side of the pouch is not ornamented.

I claim:

The ornamental design for a combined purse mirror and pouch, as shown and described.

Signed at New York, N. Y., this 13th day of August, 1931.

CLEMENS KAMMERER.
